SOFA

Howard W. Maurer, East Palestine, Ohio, assignor to The Kenmar Manufacturing Company, East Palestine, Ohio, a corporation of Ohio

Application August 6, 1952, Serial No. 20,935

Term of patent 14 years

(Cl. D15—11)

To all whom it may concern:

Be it known that I, Howard W. Maurer, a citizen of the United States, residing at East Palestine, in the county of Columbiana and State of Ohio, have invented a new, original, and ornamental Design for a Sofa, of which the following is a specification, reference being had to the accompanying drawing, forming a part thereof.

I claim:

The ornamental design for a sofa, as shown.
HOWARD W. MAURER.
